TRACTION INCREASING DEVICE FOR DUAL WHEELS

Homer Schoniwitz, Alexandria, La.

Application June 12, 1941, Serial No. 397,775

1 Claim. (Cl. 152—220)

This invention relates to new and useful improvements in traction increasing devices and more particularly to an appliance for dual wheels.

The principal object of the present invention is to provide a traction increasing device which can be readily installed on dual wheel assemblies where at present it is difficult to apply traction increasing device due to the close approximation of the wheels.

Other important objects and advantages of the invention will become apparent to the reader of the following specification.

In the drawings:

Figure 1 represents a side elevational view of a dual wheel assembly with the traction increasing devices installed.

Figure 2 is a vertical sectional view through the structure shown in Figure 1.

Figure 3 is a side elevational view of the annulus.

Figure 4 is a fragmentary side elevational view showing a pair of the traction increasing elements.

Figure 5 is a top plan view of one of the traction increasing elements.

Figure 6 is a perspective of one of the keys.

Referring to the drawings wherein like numerals designate like parts, it can be seen that the dual wheel assembly is generally referred to by numeral 5 and consists of a pair of rims 6, mounted on disks 7, 7 of substantially frusto-conical shape, the central portions of these disks 7 being secured together by suitable means 8. With the wheel disks 7, 7 secured together, a V-shaped annular trough is defined in which a portion of the present invention is disposed.

The portion of the present invention which is disposed into the V-shaped trough is an annulus 9 of substantially triangular cross section and this annulus 9 is provided with circular laterally disposed bosses 10 which fit into correspondingly-shaped openings in the disks 7. Obviously, the disposition of these bosses into the openings of the disks prevents rotation of the annulus 9 independently of the wheel assembly. Furthermore, the dual wheels have to be separated before the annulus can be applied.

The traction increasing devices each consists of T-shaped cleats 11, which include a base plate 12 and ribs 12' projecting radially from the wheel. A segmental annular plate 13 extends inwardly

between the tires 14 on the rims 6 and each segment 13 has two shanks 15 which are disposed into corresponding recesses 16 in the annulus 9. The plate 13 has its side walls flared to provide a broad peripheral surface 13' to which the base plates 12 of the cleats are welded in obliquely disposed position.

Extending transversely through the annulus 9 and through the bosses 10 are openings 17 certain of which register with notches 18 in the shank 15.

When the shanks 15 have been properly fitted into the pockets 16 of the annulus 9, pins 19 can be disposed through the openings 17 and these pins or keys will pass through the notches 18 and thus prevent the traction increasing elements from becoming displaced with their cleats 11 bridging the tires 14 in the manner shown in Figure 2.

One end of each of the pins or keys 19 is bent to provide a snap fastener 20 which can be snapped into one of the openings 17, thus preventing accidental displacement of the key from its detent acting position.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a dual wheel assembly including a pair of wheels detachably connected together and having outer parts diverging outwardly to provide an annular space between them which is of substantially V-shape in cross section with said parts having lateral holes therein, an annular member of V-shape in cross section fitting in the V-shaped space and having bosses at its sides fitting in the holes in the divergent parts, said annular member having radiating sockets opening out through its outer circumference, a plurality of segmental members having inwardly extending shanks thereon for fitting in the sockets, means for detachably holding the shanks in the sockets and lug carrying members connected with the outer edges of the segmental members and extending over tread portions of the dual wheel assembly.

HOMER SCHONIWITZ.
